UNITED STATES PATENT OFFICE

WARREN H. MCLEOD, OF BOULDER, COLORADO

GOLF TEE

Application filed October 17, 1928. Serial No. 313,047.

This invention relates to a novel form of golf tee or golf tee unit which may be used singly or which may be, together with other tees of like structure, pyramided to obtain 5 tees of varying heights.

It frequently occurs that the character of the course makes it desirable to position the golf ball for teeing off at a greater elevation than that afforded by a single tee or tee section. Furthermore, there is no uniformity 10 in the height of tees employed by different players, each player having his own idea as to the proper height of tee suited to his particular stroke.

Sectional golf tees have heretofore been employed to give different elevations for the golf ball. In most instances such tees have, however, been of the re-useable or permanent variety, all of the sections of the tee 20 being interconnected but so arranged that any desired number of sections could be employed.

It is an object of the present invention to provide a golf tee section which is entirely 25 independent of other sections and capable of use alone as a complete tee but of such structure that it can be intermeshed with a like tee section to permit pyramiding of two or more tee sections.

It is also an object of the invention to so construct the tee sections that when they are intermeshed in one manner, the total height of the resulting pyramided tee formed from two tee sections will be greater than when 35 the same two tee sections are intermeshed in a different manner, whereby at least two different heights may be obtained by pyramiding two tee sections.

It is a further object of the invention to 40 provide a single reversible tee section which, when in one position, will hold a golf ball at a greater elevation than when in the reverse position.

A still further object is to provide a golf 45 tee having serrated ends whereby the tee will

be self-anchoring when placed on the teeing ground, the serrations also functioning to interlock the tee with a similar tee when pyramiding is desired.

The invention will be more readily understood by reference to the drawings forming a part of this specification, in which:

Figure 1 is a side elevational view of a preferred form of golf tee section;

Fig. 2 is a cross sectional view of the tee 55 shown in Figure 1 with one end of the tee presented for receiving a golf ball;

Fig. 3 is a view similar to that in Figure 2, showing the opposite end of the tee presented for receiving the golf ball;

Fig. 4 is a view showing two tee sections 60 intermeshed in one manner;

Fig. 5 shows two tee sections intermeshed in a second manner;

Fig. 6 shows two sections intermeshed in 65 a third manner;

Fig. 7 is a view in side elevation of a modified form of tee section;

Fig. 8 is a sectional view of the tee section shown in Figure 7 showing one end of 70 the tee presented for receipt of a golf ball;

Fig. 9 is a sectional view similar to Figure 8, showing the opposite end of the tee presented for receipt of a golf ball;

Fig. 10 is a sectional view showing the 75 manner in which the modified form of tee section shown in Figure 7 may be pyramided.

Referring to Figure 1, the tee section is indicated generally at A, and has the relatively shallow serrations Y at one end and 80 the deep serrations X at the opposite end. It will be noted that the tee is reversible and can be placed in position so that the serrations X will contact with the ball or so that the serrations Y will contact with the ball. 85 An important feature of the structure of the tee resides in the fact that the teeth 1 of the serrations X are inclined downwardly from the periphery of the tee toward the center of the tee, as more particularly shown in Figure 90

2. The upper end of a tooth 1 of the serrations X as indicated by the reference character 3, while the inner lower end is indicated at 4. It will thus be seen that when the serrations X contact with the ball, that the ball is supported on the points 3 of the teeth 1 in an annular ring having a diameter substantially equal to the outside diameter of the tee. When, on the other hand, the serrations 10 Y are at the upper end of the tee and the ball supported thereon, the ball will be supported by the inner points of the teeth 2 of the serrations Y since the teeth 2 do not incline downwardly from the periphery of the tee. This 15 will be apparent from an inspection of Figure 3 wherein the face of the teeth 2 is indicated at 5. Due to the fact that the teeth 1 of the serrations X at one end of the tee are inclined as above described, it will be appreciated that the golf ball is supported by a substantially annular bearing of greater diameter than the diameter of the annular bearing surface presented to the ball when seated upon the end of the tee provided with 20 the serrations Y. Due to the fact that the ball when seated on the end of the tee provided with the serrations X is supported by an annular bearing of greater diameter, it will be appreciated that the ball sets down in 25 the tee to a greater extent than when supported on the end of the tee provided with the serrations Y.

When it is desired to procure a greater height of tee than that of a single tee section, two or more tee sections may be intermeshed to secure the desired height. The structure of the tee section shown in Figure 1 is such that when combined with another tee section of like form, the two tee sections may be intermeshed in any one of three 35 positions according to the desire of the player.

In Figure 4 two of the tee sections are shown pyramided with their serrations X intermeshing, while in Figure 5 the two sections are shown pyramided with the serrations Y intermeshed. Since the serrations X are of much greater depth than the serrations Y, it will at once be appreciated that when two sections are pyramided by intermeshing the deep serrations X, the sections are telescoped together to a greater degree than when pyramided by intermeshing the relatively shallow serrations Y, with the result that when pyramided by intermeshing the deep serrations X, a shorter pyramided tee is secured than when the sections are pyramided by intermeshing the shallow serrations Y.

In some instances a player may desire to have the ball rest lightly upon the tee rather than to be set deeply in the tee. This result is obtained when using a single tee by placing the ball on the end of the tee provided with the serrations Y. When pyramiding the tees, a selection of the character of the seating surface provided for the ball may be

had by pyramiding two sections as shown in Figure 6. When the sections are pyramided in the fashion shown in Figure 6 they are of the same height as when pyramided in the manner shown in Figure 5 but a selection of the character of the seating surface provided for the ball may be provided since by reversing the pyramided tee, the ball may be seated either upon the serrations Y of one tee section or the serrations X of the other tee section.

In the use of the tee shown in Figure 1 in any of the ways above described, it will be appreciated that a serrated surface is always presented both to the ground and to the ball, thus providing for the self-anchoring characteristic of the tee due to the fact that the serrations penetrate into the soil and hold the tee in any desired adjusted position.

In the modified form shown in Figures 7 to 10 the tee section is provided with an annular bearing surface for receiving the ball at each end of the tee, the annular bearing surface 10 at one end of the tee being smaller than the annular bearing surface 11 at the opposite end of the tee. In this way, the ball seats deeper into the tee when the annular surface 11 of greater diameter is contacting therewith, as shown in Figure 9, than when the annular surface 10 of less diameter is contacting with the ball, as shown in Figure 8. In this regard the modified form is similar to the preferred form shown in Figures 1 to 6.

The modified form of tee may also be pyramided with tees of similar structure, as clearly shown in Figure 10. It is, however, not possible to secure varying heights of a pyramided tee formed from two tee sections when employing the modified form shown in Figures 7 to 10.

Golf tees conforming to the invention are preferably formed from plastic clays or earths in such manner as to be disintegrable when struck by a golf club in play. The invention, however, in its broader aspects is applicable to tees constructed from any suitable material.

Having thus described my invention, what I claim is:

1. A golf tee unit comprising a hollow cylindrical section having serrated ends, the serrations at one end of the section varying in depth with respect to the serrations at the opposite end.

2. A reversible golf tee having a substantially annular bearing surface for receiving a golf ball at each end thereof, the diameter of the bearing surface at one end of the tee being greater than the diameter of the bearing surface at the opposite end of the tee.

3. A golf tee unit comprising a hollow ended tee section provided with interlocking

means at each end thereof selectively engageable by the ends of a like tee section.

4. A golf tee unit comprising a hollow ended tee section provided with interlocking serrations at each end thereof selectively engageable with the serrations of a like tee section.

5. A golf tee unit comprising a hollow ended tee section provided with interlocking serrations at each end thereof selectively engageable with the serrations of a like tee section, the serrations at opposite ends of the sections being of different depth.
